UNITED STATES PATENT OFFICE.

WILLIAM E. ROBERTS, OF YONKERS, NEW YORK, ASSIGNOR TO PARAMOUNT RUBBER
CONSOLIDATED, INC., OF TUCKAHOE, NEW YORK, A CORPORATION OF DELAWARE.

METHOD OF MAKING HOT-WATER BOTTLES.

Application filed December 8, 1924. Serial No. 754,499.

Hot water bottles hereto made have frequently necessitated the use of cement after vulcanization in order to join parts left separate for the removal of the core, or to position the threaded ferrule which receives the bottle stopper and to prevent rotation thereof with reference to the bottle whenever the stopper is inserted within, or removed from the bottle. The varying degrees of temperature to which the bottle is subjected when in use frequently loosens the cement, which results in an ineffective junction of the co-operating parts.

One of the objects of my invention, therefore, is the provision of means for enabling an effective junction to be made between the ferrule and the neck of a hot water bottle, so as to obviate the necessity for the use of cement or other material applied after vulcanization, and to effectively resist the tendency of the rotated plug to twist the ferrule free from the neck.

A further object of my invention is the provision of means for enabling a hot water bottle to be satisfactorily suspended from a vertical surface without necessitating the use of fastening members, which are attached to the supporting surface. To this end, I contemplate the use of a sucker which is carried by the bottle and is adapted to engage the vertical surface and to adhere thereto, whenever the air is excluded from the face of the sucker and the supporting surface. In this connection, my invention is directed towards the provision of means whereby the sucker may be formed in a simple manner, and homogeneously united with the rubber either during the forming or vulcanizing operation.

The preferred means for carrying out my invention is illustrated in the drawings wherein Fig. 1 is a plan view of the bottom section of a forming mold employed for carrying out my invention; Fig. 2 is a perspective view of a threaded ferrule with a sleeve of rubber attached thereto; Fig. 3 is a vertical section taken through the forming mold and illustrating sheets of rubber seated therein; Fig. 4 is a detailed view illustrating part of a hot water bottle having the neck portion in section; Fig. 5 is a section taken on the line 5-5 in Fig. 4; Fig. 6 is a plan view showing the bottom section of a vulcanizing mold; Fig. 7 is a vertical section

taken through a portion of the bottom mold 55 indicated in Fig. 6, and showing the manner in which a supporting pad may be formed; Fig. 8 is a section similar to that shown in Fig. 7 and showing the forming ring in position; Fig. 9 is a vertical section showing parts of the assembled vulcanizing mold with the hollow rubber article placed therein; Fig. 10 is a perspective view showing a part of the finished article; and Fig. 11 is a perspective view of the mandrel 65 shown in Fig. 9.

I have illustrated my invention in connection with the manufacture of a hot water bottle. The molds for forming the article are illustrated as comprising a lower mold 70 section 10 and an upper mold section 11 which have cooperating recesses in which the hollow rubber article is formed. Section 10 is shown as being provided with passageways 12 which lead to a common passageway 13, while the upper section is illustrated as having spaced passageways 14 which lead to a common passageway 15. Connections are shown at 16 and 17 respectively for enabling a vacuum to be produced in the 75 respective passageways 13 and 15.

The vacuum within the passageways is employed for seating sheets of rubber stock within the respective mold sections. The article thus formed is made from a lower 80 sheet A and an upper sheet B which are united at the marginal edges when the respective sections are brought together. Before the sections are brought together, however, a mandrel 20 having a ferrule 21 85 threaded thereto is placed within the rubber lined lower mold section adjacent the neck of the bottle.

To insure an effective connection between the ferrule 21 and the rubber comprising the body portion of the bottle I may cover the outer surface of the ferrule with raw rubber and then mold it to the shape shown in Fig. 2 and subsequently semi-cure it so as to make it adhere to the ferrule and preserve its shape. In the embodiment shown in Fig. 2, the coating indicated at 23 has ears 24 which project laterally therefrom, and on diametrically opposite sides of the ferrule. The coating terminates adjacent the ends of the ferrule, whereby the ferrule may be threaded onto the shank 25 of the mandrel.

When the mandrel is laid within the cavity of the lower mold section, the ears 24 are disposed adjacent that portion of the rubber which forms the seams at the shoulders of hot water bottles. Accordingly, when the co-operating mold sections having sheet rubber stock inserted therein are brought together, the ears are compressed by the rubber adjacent the seam, and thereby 10 are firmly embedded in such manner as to prevent rotation of the ferrule with reference to the neck of the bottle. The effect of such action is illustrated in Fig. 5, wherein the seam forming portion of the rubber 15 surrounds the ears so that when the article is vulcanized the coating 23 becomes united with the rubber forming the body of the article.

In making the neck of the bottle, I have 20 shown the lower mold section being so formed that a tab 30 is formed as an extension of the bottle funnel. The tab functions to support a button or "sucker" 31 which is so shaped that the bottle may be 25 suspended upon a vertical wall or other supporting surface whenever the button is pressed against the wall with sufficient pressure to exclude the air between the button and the supporting surface.

30 A simple way of forming the button and attaching it to the tab is illustrated in Figs. 6 to 9, wherein the lower mold section 10 has a cavity 40 at the bottom of which a protuberance 41 is formed. A mass of rubber C is placed within the cavity as shown 35 in Fig. 7 whereupon a forming member, preferably a split ring 42 is inserted into the cavity, and over the rubber C and pressed downwardly until the rubber is forced 40 slightly out of the ring opening as shown in Fig. 8.

The mold sections having the cavity 40 and the protuberance 41 therein, may comprise either the forming or vulcanizing 45 mold. In either case the rubber C' which extends through the opening within the ring is pressed against the rubber forming the tab which is backed by an extension 27 of the mandrel when the mold sections are 50 brought together. Then when the article is vulcanized the button is united to tab while the ferrule coating is completely cured during the same operation.

An important advantage of a hot water 55 bottle made in accordance with my invention is the fact that the metal ferrule which receives the stopper may be securely fastened to the neck of the bottle without necessitating the use of rubber cement applied 60 after vulcanization or similar fastening expedients. A further advantage is the fact that the section supporting tab may be united with the rubber which forms part of the bottle in a very simple and expeditious 65 manner.

Having thus described my invention, I claim:

1. A method of making a hot water bottle comprising the seating of sheets of rubber within cooperating mold sections, bringing 70 the sheets together upon an interposed ferrule having lateral projections associated therewith, and exerting pressure on the sheets to join them and clamp the projections within the seams. 75

2. The method of making hot water bottles comprising forming the body of the article with a neck portion and an upward extension, causing the rear side of the upward extension to adhere to a rubber button 80 portion, and vulcanizing the body and button as a unit with the button having a concave rear face.

3. The method of making hot water bottles comprising seating by suction two sheets 85 of rubber in main cavities for the body of the article bringing such rubber lined cavities together upon an interposed mandrel, carrying the ferrule portion, causing the main portion of the bottle to engage rubber 90 contained in an undercut cavity in a mold member, and vulcanizing the parts together. 95

4. The method of making hot water bottles comprising surrounding a metal threaded ferrule with rubber formed with 100 a projecting portion, semi-curing such coated ferrule, seating rubber for the body and the neck of the bottle in a pair of cavitary molds, mounting the coated ferrule on a mandrel and placing it within one of the rubber 105 lined cavities and bringing the two members together, said mold members having raised cutting edges adapted to press the two sheets of rubber together to form a seam, the projection on the coated ferrule lying between the side sheets of the body. 110

5. The method of making hot water bottles comprising surrounding a metal threaded ferrule with rubber formed with diametric projecting portions, semi-curing 115 such coated ferrule, seating by suction two rubber sheets for the body and the neck of the bottles in a pair of cavitary molds, mounting the coated ferrule on a mandrel and placing it within one of the rubber lined cavities and bringing the two rubber lined mold members together to form a seam, the 120 projections on the coated ferrule lying within the seams at the shoulders of the body. 115

6. The method of forming a suction tab 120 on a rubber article comprising the seating of rubber within a mold cavity, and bringing the article into contact with rubber which protrudes through a removable hollow member, and vulcanizing the parts of 125 the article together.

7. The method of forming a suction tab for a rubber article comprising the seating a mass of rubber within a mold cavity, placing a ring over the rubber so as to form it

to the desired shape, bringing the article into contact with part of said rubber, vulcanizing the article with the ring in place, and then removing the ring after the vulcanizing operation.

8. The method of making a hot water bottle having a sucker attached thereto, comprising the taking of a mold section having a recess therein, and also having a cavity extending below the recess, placing a mass of raw rubber within the cavity, positioning a hollow member also within the cavity in such manner as to force part of the rubber through the member, bringing a portion of the article to which the tab is to be attached into contact with that portion which extends through said member, exerting pressure upon the article so as to cause adherence between the portions of rubber which are in contact with each other, and

then uniting the rubber during the vulcanizing operation.

9. The method of forming a sucker for hot water bottles, comprising the placing of a mass of raw rubber within a hollow cavity, 25 shaping the rubber into the desired form by the insertion of a split ring, exerting pressure upon the ring until the rubber is forced outwardly through the center of the ring, whereby part of the rubber protrudes 30 beyond the outer surface of the ring, then bringing a portion of the hot water bottle into contact with the rubber which protrudes from the ring and subsequently uniting the rubber to the bottle during the vul- 35 canizing operation.

In testimony whereof, I hereunto affix my signature.

WILLIAM E. ROBERTS.
